UNITED STATES PATENT OFFICE.

ALFRED H. WIEDHOFFT, OF LAKE VIEW, ILLINOIS.

SEED-DROPPER.

SPECIFICATION forming part of Letters Patent No. 351,950, dated November 2, 1886.

Application filed May 17, 1886. Serial No. 202,403. (No model.)

To all whom it may concern:

Be it known that I, ALFRED H. WIEDHOFFT, residing at the town of Lake View, in the county of Cook and State of Illinois, have invented certain new and useful Improvements in Seed-Droppers, of which the following, in connection with the accompanying drawings, is a specification.

My invention relates to that class of agricultural implements intended for the purpose of dropping seed—such as corn—in rows. My purpose is to improve the means employed for throwing the dropping mechanism in and out of gear with the means employed for driving or actuating it. I also aim to provide improved means for regulating the distance between the rows of seed to be planted, all of which will hereinafter be more fully explained, and set forth in my claims.

In the drawings, Figure 1 is a side elevation of so much of a seed-dropper as is necessary to be shown for the proper illustration of my invention. Fig. 2 is a top view of the principal parts of the same. Fig. 3 is a front view of the parts operating to reciprocate the seed-slide. Fig. 4 is a detail, the same being a front view of the gravitating plate or loaded or weighted finger and its engaging-wheel, forming a part of the slide-moving mechanism. Fig. 5 is a section in the plane of the line $x-x$ of Fig. 4, viewed in the direction indicated by the arrow there shown. Fig. 6 is a detail, the same representing a portion of the inner face of the expandable and contractible wheel; and Fig. 7 is a section in the plane of the line $x-x$ of Fig. 6, viewed in the direction indicated by the arrow there shown.

Like letters of reference indicate like parts.

A represents the frame of the machine. B is the land-wheel applied to an axle, C, which turns at one end in bearings or in a box, a, applied to the frame A.

D D are the seed-boxes, and E is the seed-slide.

F F are the seed-tubes. G G are the runners.

All of the parts now referred to are old and well known, and their construction and operation are familiar to those acquainted with machines of this class. I have not, therefore,

here aimed to describe these parts with particularity, but have merely shown a form of construction which I deem will be suited to my improvements. I desire to state, however, that my improvement may be applied with advantage to seed droppers constructed differently from the particular example I have shown, so far as relates to the parts already described. 55

H is a drive-wheel, which is expandable in the direction of its perimeter and rigidly applied either to the wheel B or to the axle C. To render this rigid attachment to the axle capable of being made with facility, I make a circular flange, a', on the said axle, and I pass bolts a" a" through the wheel H and through the said collar, holes being made for that purpose at the proper place, and on the screw-threaded ends of these bolts I run nuts a" a", thus clamping the parts firmly together, so that the said wheel and shaft will be rotated together. The means employed for connecting these parts rigidly together is not, however, an essential feature of my invention, as this rigid connection may be made in any well-known or suitable way. In the wheel H, I make radial slots b b. The outer face of the wheel H is by preference beveled near its perimeter, as is clearly indicated at e, in Fig. 7. 7c

H' H' are plates having radial lateral edges, 80 and the upper parts of which are outwardly bent or flaring, as shown at d. I apply a series of these plates to the wheel H by means of bolts e e, (passing through the said plates and through the slots b b,) and nuts e' e' run upon the said bolts. The plates H' H' are thus made radially adjustable and a grooved perimeter is formed, the diameter of which may be either increased or diminished by adjusting the plates H' H' a greater or less distance from the center of the wheel H. 85

I is a wheel or pulley turning on a fixed shaft, I', applied by means of an extension or bar, I", to the forward part of the frame A. On the inner face of the wheel I are radial depressions f f. 90

J is a drive belt running on the wheels H and I, and on a vertically-adjustable wheel, K. The wheel K may be made vertically adjustable in any suitable or well-known way. 100

In the example shown *g* is a plate depending from the axle *g'* of the wheel *K*, and this plate has therein a slot, *h*. A fixed plate, *g''*, is attached to the frame *A*, and has thereon ribs 5 or flanges *i i*, between which the plate *g* moves, the said flanges serving as guides therefor. A fixed screw-pin, *j*, projects outwardly from the plate *g*, and *k* is a nut run upon the screw-threaded part of the said pin. By loosening 10 this nut the wheel *K* may be either raised or lowered, and it will be held or clamped in the position in which it may be set by tightening the said nut. The function of the wheel *K* is to preserve the proper tension of the belt *J*, 15 it being understood that its tension or slack is varied as the position of the plates *H' H'* is varied, or as the said plates are set either more or less distant from the center of the wheel *H*. It will now be perceived that the 20 wheel *I* may be rotated with more or less speed in comparison to the speed of the rotation of the wheel *H* by either expanding or contracting the latter wheel in the manner now described, and hence that the seed may be dropped 25 with greater or less frequency, or in rows more or less apart, as may be desired. This space, therefore, as will now be perceived, may be regulated by means of the expansible and contractible wheel *H*.

30 *L* is a gravitating or weighted plate hung loosely or freely on the shaft *I'*, and having thereon a pin or finger, *L'*, and an outwardly-projecting lug, *f'*, adapted to enter the depressions or sockets *f f* in the wheel *I*. The plate 35 *L*, as will be observed, is arranged next to the inner face of the wheel *I*, and is capable of sliding from the said wheel to a sufficient extent to permit the lug *f'* to be drawn out from the socket *f*, in which it may be engaging. It 40 is to be understood that, while the said lug projects into any one of the said sockets the said wheel and plate are in engagement and are rotated together for that reason.

L'' is a hub on the plate *L*, and *l* is a groove 45 in the said hub.

M is a sliding bar clasped to the axle-extension *I''*, and having its outer end bent to enter the groove *l*.

N is a vibrating arm pivoted at its lower 50 end to the frame *A*, and weighted at its upper end, as indicated in Fig. 3.

O is a link or pitman connecting the slide *M* and arm *N*, being pivoted or jointed at its ends to the said slide and arm, respectively. 55 By tilting the arm *N* toward the wheel *I* the plate *L* will be pushed into engagement with that wheel, the link *O* acting on the slide *M* and the latter on the hub *L''*, so as to produce that result. By tilting the arm *N* in the opposite direction the part *L* will be drawn from its engagement with the wheel *I*. The arm *N* being weighted, as described, will retain it under ordinary circumstances in either inclined position in which it may be set; but its 65 position may be reversed with facility, as may be desired.

P is a pin or small shaft, turning in bearings *n n* on the extension *I''*.

Q is an arm or lever rigidly attached at one end to the shaft *P*. 70

Q' is also an arm or lever rigidly attached to the said shaft, and arranged at an angle to the arm *Q*.

R is a finger-knuckle, jointed to the outer end of the arm *Q* in such a manner as to form 75 a straight extension thereof, but also so as to be capable of being folded yieldingly only in the direction of the wheel *K*, any spring being employed to return the said finger to its original position after it has been pushed in the 80 said direction and released.

S is an arm pivoted at one end to the arm *Q*, and at the other to the slide *E*, and *T* is a close spring, connected to the arm *S* and to a fixed pin, *o*. As the wheel *I* is rotated while 85 in engagement with the plate *L*, the finger or pin *L'* strikes the finger *R* in such a manner as to move the lever *Q'* in a forward direction or toward the front of the machine, thus throwing the arm or lever *Q* out laterally and moving the slide *E* in the same direction, owing to the connection of that slide with the arm *Q* by means of the arm *S*. After the finger *L'* has slipped past the finger *R*, the spring *T* returns the slide *E* to its original position, and this 90 movement of the said slide results in the finger *R* also being returned to its original position, as will now be observed especially on reference to Fig. 2. The slide *E* is thus reciprocated so that the seed will be dropped at the proper 95 times.

I desire to call attention to the fact that the plate *L* is so formed that it serves as a weight to the finger *L'*, always bringing that finger directly over the shaft *I'* whenever the said plate is disengaged from the wheel *I*. It will therefore make no difference what particular depression *f* is directly under the shaft *I'* when the plate *L* is pushed toward the wheel *I*, for the engagement of the said wheel and plate will occur while the said finger stands vertically, or nearly so, which is its proper position when engagement occurs. It is to be understood, of course, that the seed-slide is not reciprocated when this engagement does not exist. When the wheel *I* is rotated in such a direction as to cause the finger *L'* to strike the forward side of the finger *R*, the latter will yield or be folded in such a manner that the lever *Q'* will not be actuated. The seed-slide 110 will not, therefore, then be moved.

The object of the jointed finger *R* is to prevent the seed from being dropped and the parts from becoming disarranged when it becomes desirable to back the machine while in gear; and the function of the weight or counterpoise upon the plate *L* is to cause the tripping-finger *L'* to automatically assume a vertical or other fixed normal position with relation to the arm *Q*, when thrown out of gear or disengaged 125 from contact with the wheel *I*, thus enabling the operator to know that, when in starting at 130

the end of a row, if his machine is in alignment with the cross rows, the finger L' will, upon throwing the machine into gear, engage the tripping mechanism at the proper time 5 and drop the seed accordingly without any preliminary mechanical adjustment.

Having thus described my invention, what I claim as new, and desire to secure by Letters Patent, is—

10 1. The combination, in a seed-dropper, of an expansibly adjustable and detachable drive-wheel with a seed-slide and a gravity-clutch member, having a tripping-finger for actuating said seed-slide, and a pulley connected 15 with and propelled by said drive-wheel and forming a counterpart of said clutch, whereby said tripping-finger may be caused to assume a given normal position with relation to the working parts of the machine when said clutch 20 members are disengaged, substantially as and for the purposes set forth.

2. In combination with the seed-dropping mechanism of a corn-planter, the gravity-clutch member L', arranged to assume a vertical position when said clutch is released, substantially as and for the purposes set forth.

3. A seed-dropper in which the drive-wheel and seed-slide are in combination with an ad-

justable counterbalanced finger or trip device, substantially as and for the purposes specified. 30

4. The combination, in a seed-dropper, of the counterbalanced laterally-adjustable plate L, having thereon a finger, L', and a lug, f', the wheel or pulley I, having therein a series of depressions, f f, the shaft I', and a pivoted 35 lever in operative connection with the seed-slide, substantially as and for the purposes specified.

5. The combination, in a seed-dropper, of the wheel or pulley I, having therein a series 40 of depressions, f f, the plate L, having thereon a finger, L', a lug, f', and a grooved hub, the shaft I', passing freely through the said wheel and plate, a slide engaging the said hub and in connection with an operative lever, the shaft 45 I', the lever Q Q' R, the arm S, the spring T, and the slide E, substantially as and for the purposes specified.

In testimony that I claim the foregoing as my own I hereby affix my signature in presence of two witnesses.

ALFRED H. WIEDHOFFT.
